UNITED STATES PATENT OFFICE.

BENJAMIN KENOYER, OF MARQUETTE, NEBRASKA.

CORN-PLANTER.

SPECIFICATION forming part of Letters Patent No. 340,670, dated April 27, 1886.

Application filed September 10, 1885. Serial No. 116,726. (No model.)

To all whom it may concern:

Be it known that I, BENJAMIN KENOYER, a citizen of the United States, residing at Marquette, in the county of Hamilton and State of Nebraska, have invented certain new and useful Improvements in Corn-Planters; and I do declare the following to be a full, clear, and exact description of the invention, such as will enable others skilled in the art to which it app pertains to make and use the same, reference being had to the accompanying drawings, and to the letters and figures of reference marked thereon, which form a part of this specification.

15 My invention combines a device for marking the rows with the planter, and is operated by power derived from the rear ground-wheels. The operator, seated upon the machine, besides driving the team, easily controls and adjusts 20 the various parts of the machine by means of convenient levers.

The accompanying drawings illustrate the different features of the invention, in which Figure 1 is a plan view of the machine. Fig. 25 2 is a vertical side view. Fig. 3 is a sectional view on the line xx of Fig. 1. Fig. 4 is a cross-section on the line yy of Fig. 1. Fig. 5 is an enlarged detail of the feed-wheel. Fig. 6 is a vertical section of feed-spout.

30 Letters of reference are used to denote the parts of the invention, similar letters denoting corresponding parts in the different views.

The letter A indicates the main frame of the machine, which supports a seat, A', for the 35 operator.

To the frame A is journaled the shaft B, bearing the fixed toothed wheels bb and b' and a loose sprocket-wheel, C, having a pawl, i' , adapted to engage the teeth in wheel b' when 40 the latter has a forward motion. The ground-wheels CC are also on the shaft B, adjacent to the cog-wheels bb , which are actuated by the ground-wheels by means of the pawls $i i'$, pivoted to the said ground-wheels and engaging 45 the teeth of the wheels bb in their motion forward.

Across the front end of the frame A is a bar, a , on which is a loose sprocket-wheel, a' . Attached to the bar a is a lever, e , whose fulcrum 50 is the shank of a caster-wheel, E, which is held in place by suitable guides, $e' e'$, on the frame A, and which sustains the weight of the for-

ward part of the machine when the handle of the lever is depressed, the shoes D D of the planter being raised clear from the ground by 55 this means. Pins $p p$ on the lever G hold the lever-handle e in the desired position.

T is the tongue, attached to the hounds $d d$ on the frame A.

I have now described the main frame and 60 running-gear of my planter, from which description it will be seen that it may be readily turned in any direction or be easily impelled forward or backward. I now proceed to describe the marking and planting mechanism. 65

F is an adjustable frame, resting upon the main frame A above the feed-shoes D D. The frame F is moved forward or backward by means of the lever G. The lower end of the lever G is pivoted to a hanger on the frame A, and two 70 rods, gg , connect it with the frame F. The pins $p p$ on this lever are adapted to engage the notches $t t$ on the lever e , by which means it is held in position. A shaft, H, is journaled in the frame F, and extends on each side beyond it. To the ends of this shaft are connected by knuckle-joints the extensions hh , bearing the markers I I. The extensions hh are held in position by the supports ff , having the guides $f' f'$, which allow a vertical 75 motion of the arms. A sprocket-wheel, K, on the shaft H is adapted to engage a belt-chain, c' , which passes around the toothed wheels b' and a' , by which it is made to revolve. By means of the pedal-lever P, having the spool 80 r , the chain c' is disengaged from the wheel K, when desired.

M M are blocks attached to the side of the frame F, and are furnished with a vertical opening, s , through which the grain drops into 90 the spout R, and a slot, s' , for the beveled cog-wheel n . The feed-box N rests upon the block M. The bottom of the feed-box consists of a beveled cog-wheel, O, adapted to engage the cog-wheel n . The wheel O has a grain-hole, 95 o , which at each revolution coincides with the hole s in the block M. A screw-shank holds the wheel O in position. An ordinary cover is provided for the box N.

In the spout R is a slat or strip, v , pivoted 100 near its center. It stands diagonally across the spout, its upper end being pressed against the front side of the spout by a spring, w . A pin, u , on the wheel n at each revolution

strikes the upper end of the slat and forces it back until its lower end has moved sufficiently to allow the grain to drop out into the ground, when it is forced by the spring into 5 its former position.

The parts of the marker and feeder are set so that the impressions of the marker and the grain, when dropped, are in alignment.

The frame F is made adjustable, so as to regulate the distance between the rows and to set the markings in line with those already made on commencing a new row.

I am aware that the general form of my planter is not new, and I do not broadly claim such 15 as my invention.

What I do claim, and desire to secure by Letters Patent of the United States, is—

1. In combination with a frame, A, and

running gear, the movable frame F, shaft H, sprocket-wheel K, blocks M M, having the 20 holes s and slot s', beveled cog-wheel n, having a pin, u, a cog-wheel, O, having a hole, o, box N, spout R, having a pivoted strip, v, and spring w, lever G, having pins p p, and chain c, substantially as herein described.

2. In a corn-planter, the movable frame F, having a shaft, H, sprocket-wheel K, jointed arms h h, markers I I, supports f f, having guides f' f', and lever G, having pins p p, substantially as described.

In testimony whereof I affix my signature in presence of two witnesses.

BENJAMIN KENOYER.
